[57] CLAIM

The ornamental design for an antenna topper shaped like a flaming eyeball, as shown and described.

DESCRIPTION

FIG. 1 is a left side elevation view of a antenna topper shaped like a flaming eyeball, showing my design;

FIG. 2 is a front elevational view thereof;

FIG. 3 is a rear elevational view thereof;

FIG. 4 is a top plan view thereof; and,

FIG. 5 is a bottom plan view thereof.

The surfaces not shown in the drawings or described in the specification, form no part of the claimed design.

The drawings are lined for color.
